UNITED STATES PATENT OFFICE

WILLIAM J. HELMER, OF FORT KAMEHAMEHA, TERRITORY OF HAWAII

PANORAMIC DRAWING BOARD

Application filed July 16, 1928. Serial No. 293,159.

My invention relates to improvements in panoramic drawing boards, and it consists in the combinations, constructions and arrangements hereinafter described and claimed.

- 5 An object of my invention is to provide a panoramic drawing board which will give a true perspective of the object drawn and which may be used for drawing landscapes, buildings, or in fact any kind of an object.
- 10 A further object of my invention is to provide a device of the type described which is extremely simple in construction and which may be readily explained to a novice and permit him to make an accurate sketch of an object within a very short time after being told how to operate the device.
- 15 Other objects and advantages will appear as the specification proceeds, and the novel features will be particularly pointed out in what I hereinafter claim.

My invention is illustrated in the accompanying drawings forming a part of this application, in which

20 Figure 1 is a top plan view of the device; Figure 2 is a section along the line 2—2 of Figure 1;

25 Figure 3 is a side elevation of a movable front sight used in the device;

Figure 4 is a section along the line 4—4 of Figure 1;

30 Figure 5 is a section along the line 5—5 of Figure 1;

Figure 6 is a perspective view of the sight arm and its associate mechanism;

35 Figure 7 is a top plan view of the device showing its use in making a perspective view of an object;

Figure 8 is a plan view of a modified form of the invention;

40 Figure 9 is a section along the line 9—9 of Figure 8;

Figure 10 is a plan view of another modified form of the invention; and

45 Figure 11 is a side elevation of Figure 10. In carrying out my invention, I provide a device which consists essentially of three parts, a tripod A, a sketching board B, and a drafting device C. The tripod is of standard construction and only the upper portion is shown in Figure 2.

The sketching board comprises four pieces, a bottom piece 1 intermediate triangularly-shaped pieces 2 and 3, and a top piece 4. These pieces are glued or otherwise suitably secured to each other so as to make a single unit. The pieces 2 and 3 provide a space 5 which is triangular in shape (see Figure 1). In this space 1 pivotally mount a sight arm 6 of the shape shown in Figure 6.

The sight arm has an opening 7 for slidably receiving a rear peep sight 8. This sight has an opening or peep hole 9 in the top thereof. Figure 2 shows how the sight 8 is adjustably received in aligned bushings 10 and 11 carried by the pieces 1 and 4 respectively. The bushings 10 and 11 act as a pivot point for the sight 8. The sight is adjustably secured in the sight arm 6 by a screw 12 having a knurled head.

In Figure 1 I show two broken lines D and E that indicate the extreme limits of travel of the sight arm 6 within the recess 5. The arm 6 is provided with an arcuate-shaped portion 13 which is of the same thickness as the end portion 14 (see Figure 6). The arm 70 is reduced in thickness between these portions in order to eliminate undue friction. The portion 13 slides between the pieces 1 and 4 and describes a portion of a circle about the piece 8 as a center.

The arm 6 also carries a gear housing 15 that has aligned openings in the top and bottom thereof for slidably receiving a movable front sight 16 (see Figures 3 and 6). The sight 16 has a scale 17 on one side thereof graduated in mils and a rack 18 on the other side thereof. The rack meshes with a pinion 19 (see Figure 2), and this pinion is actuated by an adjusting knob 20 (see Figure 6). A turning of the knob will raise or lower the sight 16.

The sight 16 passes through an indicator collar 21, and this collar has a ball-bearing race 22 mounted therearound. The race is received within a slot 23 of a centering cam 24 (see Figure 1) which permits the front wall 17 of the sight 16 to remain tangent to a circle having the sight 8 as its center, at all times.

The centering cam 24 is secured to a trav-

elling bar 25 having a cross-section of the shape shown in Figure 5. A strip 26 slidably holds the bar 25 in place. The bar 25 carries a triangle 27, and the edge 28 of the 5 triangle is graduated in mils in the same manner as the sight 16.

An arcuate scale 29 also graduated in mils forms a part of the upper piece 4. The lower piece 1 is arcuate in shape so as to act as a 10 support for the arcuate piece 13. A compass 30 may be inserted in the top piece 4 if desired.

From the foregoing description of the various parts of the device, the operation there- 15 of may be readily understood.

I have shown the use of the device in Figure 7. Assume that an object such as that shown at 31 is to be drawn. The device is placed in front of the object in the manner 20 shown, and the sight arm is swung to the right and to the left in order to align the sights 8 and 16 with the extreme right-hand side 32 of the object and the extreme left-hand edge 33. The movement of the sight 25 arm 6 will move the triangle 27, and the edge 28 of the triangle will designate the proper line to be drawn on the paper for indicating the right-hand side 32 of the object. The same is true when the sight arm is swung to 30 the left, and the left-hand edge 33 of the object is indicated by the line 34 on the paper.

The top and bottom of the side 32 is found upon the drawing by adjusting this sight 8 and then the sight 16, so that a person look- 35 ing through the peep hole 9 and across the top edge 35 of the sight 16 will see the top edge of the line 32. Figure 2 shows the sight 16 raised into the dotted-line position for finding, for example, the top edge of side 40 32. A person looks through the opening 9 along the broken line F, and this line con- 45 tinued will touch the top edge of side 32. The scale 17 is then read, and the number on the scale appearing just above the indicator 50 21 is noted and a dot is made on the paper opposite a like number on the scale 36 dis- 55 posed along the edge 28 of the triangle 27. This will give the top of the side 32. The lowermost point of side 32 is arrived at in the same manner, and this point is placed upon the sheet of drawing. The extremities 60 of the line 34 are now obtained, and a line 37 representing the front edge 38 of the ob- 65 ject is drawn and the extremities of this line 5 are fixed. Lines 39 and 40 connecting the lines 37 and 34 give the true perspective of the face 41 of the object.

It is obvious that before the drawing is started the tripod A is so located that the 60 entire object to be drawn may be included within the limits of the board. The board B is swung so as to align the sights 8 and 16 with the center of the object to be sketched, and the board is then clamped in this posi- 65 tion and levelled by means of a hand level.

In making a sketch of any kind, it is of prime importance that a reference point be chosen. This can be any prominent point or feature of the model object. With the sights in line with this point, reference points should be marked on the board and the sight setting recorded. It is well to refer to this reference point or points occasionally to see if the board has not been disturbed. 70

In case the board has moved, it is easy to make a re-adjustment and then continue with the sketch. Prominent or critical points of the object are marked down on the paper, and these points may be joined by a ruler. For example, in sketching a building the 75 eaves may be plotted, then the ridge of the roof, and then another prominent point in the continuation of the sketch. These points may be joined together by using a ruler, and will furnish the contour necessary for the 80 sketch. It should be remembered that any point on the model object 31 may be located by moving the sighting arm 6 horizontally and the front sight 16 vertically until the line of sight between the rear sight and the 85 front sight is brought to the desired point. These points may be joined by either straight or curved lines, according to the nature of the contour. In this way trees or other irregularly-shaped objects may be drawn with 90 substantially the same ease as buildings. 95

In Figures 8 and 9 I show a slightly modified form of the invention. The sight arm is done away with in this form, and the gear housing 50 is slidably mounted upon an arcuate rail 51 and is turned with respect thereto by a friction wheel 52 and a knurled knob 53. In all other respects the device functions in the same manner as the form already described. 100

Figures 10 and 11 show a device in which the distance between the sights 75 and 76 does not remain constant. This type of board will not produce an accurate perspective drawing, but will give close enough approximations to present an accurate-appearing sketch. The gear housing 77 in this form of the invention forms a part of a bar 78, and this bar slides in a slot 79 that is parallel with the front edge 80. A movement of the gear housing 77 to the right or to the left will vary the distance between the sights 75 and 76 to a slight extent. 110

The graduation of the edge 28 of the triangle into mils provides an easy method of transferring vertical angles into points that may be located upon a piece of paper. The co-action between the scales 17 and 36 gives an instant reading as to the various vertical points in the object desired to be transferred to the sheet of drawing. The swinging of the arm 6 in a horizontal plane gives the various horizontal points in the object. A combination of these two is all that is necessary to make an accurate perspective drawing. 120 125 130

Although I have shown and described several embodiments of my invention, it is to be understood that the same is susceptible of various changes, and I reserve the right to employ such changes as may come within the scope of the invention as claimed.

I claim:

1. A sketching device comprising a drawing board, a fixed sight thereon and a movable sight finder pivotally mounted on said board on the vertical axis of the fixed sight and being swingable about the fixed sight as a center, said movable sight being movable in a vertical and a horizontal plane, and means bearing a scale movable horizontally with the movable sight for determining points on the board spaced horizontally from each other on the object being drawn, there being a vertical scale carried by said movable sight and graduated the same as the first named scale.
2. A sketching device comprising a drawing board, a support therefor, said board being swingable into various positions upon said support, a fixed sight, a movable sight pivotally connected thereto and being swingable about the first sight as a center, said movable sight having a vertically disposed scale thereon viewable through the first sight, a scale slidable over the board and being graduated in the same manner as the sight scale, and means operatively connecting the second scale to the movable sight for keeping the second scale always directly in front of the movable sight and at right angles to the front edge of the drawing board.
3. A sketching device comprising a drawing board, a sight fixed thereon, a sight arm movable about said sight as a center, a vertically movable sight carried by said arm, means for moving said movable sight, a bar movable longitudinally of itself across the board, means bearing a scale carried by said bar and means pivotally and slidably connecting said bar and movable sight, there being a vertical scale carried by said movable sight, and graduated the same as the first-named scale.
4. A sketching device comprising a drawing board, a fixed sight, a movable sight swingable about said fixed sight as a center, a sight arm connecting said sights together, means for raising and lowering said movable sight relative to the board, a bar movable across the board parallel to the front edge thereof, a scale carried by said bar and extending normal thereto, means operatively connecting said bar and arm, whereby said scale is moved as said sight is swung, there being a vertical scale carried by said movable sight and being graduated in the same manner as the first-named scale.
5. A sketching device comprising a drawing board having an arcuate shaped rear edge, a fixed sight disposed adjacent to the

front edge of the board at the center of the arcuate edge, said sight being adjustable vertically, means securing the sight in adjusted position, an arm pivotally secured to the sight for movement over the board, a second sight carried by the free end of the arm, means for moving said second sight vertically, a bar, means mounting said bar on said board for sliding longitudinally of itself along said arcuate edge, means pivotally and slidably connecting said bar and second sight and a triangle on said bar having a graduated edge normal to said bar, there being a similar graduated vertical scale on said second sight.

6. A sketching device comprising a drawing board having an arcuate-shaped rear edge, a sight disposed adjacent to the front edge of the board and at the center of the arc-shaped edge, said sight being movable vertically and being secured in adjusted position, a sight arm pivotally secured to said first sight and being movable over the board so as to be swingable about said fixed sight as a center, a second sight carried by the free end of said arm, means for moving the second sight vertically, a bar movable across the board and parallel to the front edge thereof, a centering cam operatively connecting said bar with the free end of said arm, a triangle carried by said bar and having one of its edges extending vertically with respect thereto, and similar scales marked upon said vertical edge of the triangle and said second sight.
